J. W. KITTREDGE.
CENTRIFUGAL COMPRESSOR.
APPLICATION FILED DEC. 2, 1911.

1,110,696.

Patented Sept. 15, 1914.

UNITED STATES PATENT OFFICE.

JOHN W. KITTREDGE, OF BOULDER, COLORADO.

CENTRIFUGAL COMPRESSOR.

1,110,696.

Specification of Letters Patent. Patented Sept. 15, 1914.

Application filed December 2, 1911. Serial No. 663,485.

To all whom it may concern:

Be it known that I, JOHN W. KITTREDGE, a citizen of the United States, residing at Boulder, in the county of Boulder and State 5 of Colorado, have invented certain new and useful Improvements in Centrifugal Compressors, of which the following is a specification.

My invention relates to centrifugal air- 10 compressors and its object resides in the provision of an apparatus of simple construction, in which the centrifugal force imparted to mercury or other heavy liquid by the rapid movement of a rotary carrier, is em- 15 ployed to compress air.

By the use of my invention, air may be compressed to a considerable density by a mechanism in which accurately fitted parts such as the valves and pistons of the com- 20 pressors at present in common use, are eliminated, which does not require the care and attention necessary to maintain the ordinary compressor in operative condition which, if so desired, may be directly connected with 25 the shaft of a motor and which being of small size and weight, may be readily transported and installed wherever its services are required.

An embodiment of my invention has been 30 illustrated in the accompanying drawings in the various views of which like parts are similarly designated and in which,

Figure 1 represents a vertical, axial section of the centrifugal compressor and, Fig. 35 2, a horizontal section taken along the line 2—2, Fig. 1.

Referring to the drawings by numerals, 2 designates an air-tight housing composed of a circular body portion 3 and a cover 4 which is imperviously fastened thereon by solder or other suitable means. The interior surface of the circumferential wall of the body 3 slants inwardly toward the bottom of the same, the said bottom being concave and 45 provided at its center with an inclosed well 5 which communicates with the interior of the housing by means of a plurality of upwardly slanting passages 6 and which at the upper end of its inclosing wall communica- 50 tes with the interior of a hollow shaft 7 which projects through an opening in the cover 4, to rotate about a vertical axis in the operation of the compressor.

In the construction shown in the draw-

ings, the shaft 7 is supported by ball-bear- 55 ings 8 and 9 respectively applied to the wall of the well 5 and to the cover 4, and a sleeve 10 of elastic material is placed around the inwardly projecting bearing on the cover and a thereto adjacent enlarged portion 7^a 60 of the shaft to render the joint between the two parts impervious to air by means of the pressure of air contained in the housing.

Rigidly secured upon the shaft 7 within the housing 2, is a disk 12 which has, in- 65 teriorly, a series of radially extending ducts 20 which connect equidistant orifices in its circumferential surface with the interior of the hollow shaft at a point below a plug 13 which divides the said interior into two 70 separate compartments 14 and 15 which respectively communicate with the well in the bottom of the housing, and with the atmosphere at the upper end of the shaft. The disk 12 is furthermore provided with radial 75 passages 16 which separately connect the compartment 15 of the hollow shaft with the respective ducts at points intermediate the extremities thereof, for the purpose of sup- 80 plying the air to be compressed by the rotary motion of the disk, as will hereinafter be described, and the shaft 7 may either be di- 85 rectly connected with a rotary part of a motor or it may be provided with a power transmission device such as the pulley 17 shown in Fig. 1 of the drawings.

An annular concave deflector 18 firmly secured to the housing is interposed between the inner circumferential surface of the latter and the peripheral face of the disk for 90 the purpose of preventing the mercury which in the operation, is violently ejected through the orifices in the latter, from coming in direct contact with the body of mer- 95 cury constantly contained in the housing and thus agitating the same. The deflector furthermore increases the efficiency of the machine by keeping the mercury which, during the operation is in a concave form, from contact with the revolving disk.

A valve controlled outlet-conduit 19 con- 100 nected with an opening in the cover 3, serves to convey the air compressed in the housing to the point at which it is used.

In the operation of my invention, the 105 housing 2 is supplied with a body 21 of mercury or other heavy liquid which when the shaft 7 is at rest, extends on a level

above the orifices in the peripheral surface of the disk 12. When the shaft and the therewith connected disk are rotated at a high velocity, the body of mercury will by 5 capillary repulsion sink below the lower surface of the disk and rise proportionately along the circumferential wall of the housing whereby the revolving disk is relieved from frictional contact with the liquid. By 10 reason of the high rate of speed at which the disk is rotated, a partial vacuum is created at opposite sides of the plug 13 and air and mercury are in consequence, simultaneously drawn into the compartments 14 and 15 of the shaft, through the open ends thereof, the lower one of which communicates with the well 5 in the bottom of the housing. The mercury drawn into the compartment 14, is by centrifugal force impelled outwardly 15 through the radial ducts 20, and in passing through the same it separates into detached globules which as they pass the point of connection between the duct and the respective air-channel 16 confine a portion of the air which by centrifugal force is driven 20 through the said channel, and carry it onwardly until the globules are forcibly discharged at the circumference of the disk. The discharged bodies of mercury impinge 25 against the deflective surface of the member 18 and by their impetus move toward and over the rim thereof to fall into the body of mercury contained in the bottom-portion of the housing, without coming violently in 30 contact therewith as would undoubtedly take place if the deflector 18 were eliminated from the construction.

By making the ducts 20 tapering from 35 their points of connection with the hollow shaft, to the orifices in the circumference of the disk, the globules of mercury will, irrespective of their size, come in frictional contact with the interior surface of the ducts through which they are impelled before 40 reaching the orifice thereof and by thus closing the passage through said ducts, they will positively prevent the return flow of air. As quantity after quantity of air is thus in rapid succession discharged into the 45 housing 2 through the orifices in the disk, the air contained in said housing will be gradually compressed, to be discharged when needed, through the normally closed outlet conduit 19. Inasmuch as the compression of air is invariably accompanied by a 50 generation of heat, the housing 2 is preferably surrounded by a mantle 22 to provide a water jacket 23.

It will be understood that to increase the 55 efficiency of the machine, the disk may be provided with two or more series of ducts and air-passages, and that other variations in the arrangement and construction of the parts may be availed of within the spirit of 60 my invention.

What I claim and desire to secure by Letters-Patent is:

1. An air-compressor comprising an air-tight housing, partially filled with liquid, a rotary, hollow shaft divided into two compartments, the lower one of which communicates with the lower portion of said housing, while the upper one is in communication with the atmosphere, and a disk fixed on said shaft and provided with open-ended ducts 70 which at their inner ends communicate with the lower compartment and whose outer ends are in the periphery of the disk, and with passages connecting the upper compartment with the said ducts at points remote from 75 their inner ends.

2. An air compressor comprising an air-tight housing partially filled with liquid, a disk mounted to rotate within the same, and provided with open-ended ducts of small 80 diameter which at their inner ends communicate with the lower portion of the housing and whose opposite ends are in the periphery of the disk, and a conduit for the supply of air, the said disk having passages which 85 connect said conduit with the ducts at points remote from their ends.

3. An air-compressor comprising an air-tight housing partially filled with liquid, a disk mounted to rotate within the same and 90 provided with open-ended ducts of small diameter which at their inner ends communicate with the lower portion of the housing and whose opposite ends are in the periphery of the disk, and a conduit for the 95 supply of air, the said disk having passages which connect said conduit with the ducts at points remote from their inner ends.

4. An air-compressor comprising an air-tight housing partially filled with liquid, a 100 disk mounted to rotate within the same and provided with open-ended ducts of small 105 diameter which at their inner ends communicate with the lower portion of the housing and whose opposite ends are in the 110 periphery of the disk, a deflector interposed between the periphery of the disk and the wall of the housing, and a conduit for the supply of air, said disk having passages 115 which connect said conduit with the ducts at points remote from their inner ends.

5. An air-compressor comprising an air-tight housing, a disk having a rotary movement within the same and provided with radial, open-ended ducts which, at their 120 inner ends, communicate with the lower portion of the housing, while their outer ends are in the periphery of the disk, and a conduit for the supply of air, the said disk having 125 passages connecting said conduit with said ducts at points remote from their inner ends, and the said housing being partially filled with liquid, the level of which extends above the outer ends of said ducts when the liquid is at rest.

6. An air-compressor comprising an air-tight housing partially filled with liquid, a disk mounted to rotate within the same and provided with open-ended ducts of small diameter which taper from their inner to their outer ends, which at their inner ends communicate with the lower portion of the housing and whose opposite ends are in the periphery of the disk, and a conduit for the supply of air, the said disk having passages which connect said conduit with the ducts at points remote from their inner ends. 40
- 5 7. An air compressor comprising an air-tight housing including a water-jacket, and partially filled with liquid, a disk mounted to rotate within the housing and provided with open-ended ducts of small diameter which at their inner ends communicate with the lower portion of the housing and whose opposite ends are in the periphery of the disk, and a conduit for the supply of air, the said disk having passages which connect said conduit with the ducts at points remote from their inner ends. 50
- 10 8. An air compressor comprising an air-tight housing partially filled with liquid and provided with a bearing in its upper wall, a shaft extending through said bearing, an elastic sleeve surrounding the joint between the said bearing and the shaft within the housing, to be held in contact therewith by air-pressure, a disk on said shaft provided with open-ended ducts of small diameter which at their ends communicate with the lower portion of the housing and whose opposite ends are in the periphery of the disk, and a conduit for the supply of air, the 55 60 65 70 75 80 85
- 20 25 30 35
9. An air compressor comprising an air-tight housing partially filled with liquid, a disk mounted to rotate within the same and provided with open-ended ducts of small diameter which extend in a horizontal plane, 45 which at their inner ends communicate with the lower portion of the housing and whose opposite ends are in the periphery of the disk, and a conduit for the supply of air, the said disk having passages which connect said conduit with the ducts at points remote from their inner ends.
10. An air-compressor comprising an air-tight housing having a valve-controlled air-outlet, a disk mounted for rotation in said housing, and having an orifice remote from its axis of rotation and a duct which connects with said orifice at one of its ends, and communicates at its opposite end, with the interior of the housing at a point of lower 60 elevation than said orifice, the said disk having furthermore a passage connecting said duct with the atmosphere, and a deflector disposed between the periphery of the disk and the wall of the housing to intercept 65 matter discharged through said orifice by centrifugal force, and adapted to return said matter into the lower part of the housing.
- In testimony whereof I have affixed my signature in presence of two witnesses.
- JOHN W. KITTREDGE.
